UNITED STATES PATENT OFFICE.

CLINTON E. FROST, OF EAST CLEVELAND, OHIO, ASSIGNOR TO THE CLEVELAND OSBORN MANUFACTURING COMPANY, OF CLEVELAND, OHIO, A CORPORATION OF OHIO.

ROTARY BRUSH.

1,391,051.

Specification of Letters Patent. Patented Sept. 20, 1921.

Application filed June 24, 1918. Serial No. 241,462.

To all whom it may concern:

Be it known that I, CLINTON E. FROST, a citizen of the United States, and a resident of East Cleveland, county of Cuyahoga, and 5 State of Ohio, have invented a new and useful Improvement in Rotary Brushes, of which the following is a specification, the principle of the invention being herein explained and the best mode in which I have 10 contemplated applying that principle, so as to distinguish it from other inventions.

The present invention, relating, as indicated, to rotary brushes, is directed more particularly to the provision of an extremely 15 simple and economical brush section or brush intended for use on a suitable mandrel, and either with or without other similar sections. To the accomplishment of the foregoing and related ends, said invention, then, 20 consists of the means hereinafter fully described and particularly pointed out in the claims.

The annexed drawing and the following description set forth in detail certain mechanism embodying the invention, such disclosed means constituting, however, but one 25 of various mechanical forms in which the principle of the invention may be used.

In said annexed drawing:—

30 Figure 1 is a side elevation of half of one of my improved brush sections; Fig. 2 is a second elevation showing the other side of the same section; Fig. 3 is an end or edge view of the section shown in Fig. 1, looking 35 at the same from the right; Figs. 4, 5 and 6 are similar views showing modifications of the brush section; and Fig. 7 is a partial view in perspective of still another modification of my improvements.

40 My improved brush section involves the use of a plurality of brush material retaining means, preferably employed in the form of retaining members such as inner and outer rings which may be conveniently 45 formed of wire. The relation of these members, here shown in the form of rings, is best shown in Figs. 1, 2 and 3, in which the inner rings 1 are shown as disposed concentrically within outer spaced rings 2 and 50 3. It is, of course, immaterial as to the precise number of the inner rings 1, and in the various views I have shown both one and two of these inner rings, while in Fig. 6 I have shown the ring in the form of an annular plate 4. The rings 2 and 3 are, as al-

ready stated concentric and radially outside of the inner rings 1 and lie in different planes, one on either side of the plane of the rings 1.

The brush material consisting in the form 60 illustrated of a plurality of bristles or rather wire strands 5, is looped over the inner or base rings 1 and is then brought within or between the two outer rings 2 and 3 so that the bases of the loops are in close contact 65 against the inner ring or rings 1. The outer rings are then secured together by suitable means which tie the loops 6 together and secure the same in place upon the inner rings 1, preventing any of the bristles from becoming loose and pulling through between the two outer rings and away from the inner ring. Such retaining means conveniently take the form of the staples or wire fastenings 7, which pass through the brush 70 material and across from the wire 2 to the wire 3 at intervals around the periphery of the brush, and are so secured that they hold the two outer rings firmly together, locking the bristles in close engagement 75 therebetween, and in this way snubbing the bristles about the inner rings 1 and preventing any looseness or spreading of the loops.

My improved brush may, of course, take various modified forms, such, for example, 85 as is shown in Figs. 4 and 5, in which a double brush section is constructed by the use of two sets of the inner wires 1 placed side by side, and each having brush material looped about it, the material then all 90 clamped or tied between the outer rings 2 and 3. Still another modification is shown in Fig. 5, in which the inner rings 1 are crossed or interlocked as shown at 8, so that portions of each individual section lie in two 95 parallel planes instead of in the same plane as in the brush section of Fig. 4.

In Fig. 6 I have shown a brush similar to the brushes of Figs. 1, 2 and 3, but with the inner ring in the form of a flat annular plate 100 4, which extends from the base of the loop in the brush material to a point but slightly within the fastening staples 7. In Fig. 7 I have shown a single inner ring 1 and a single outer ring 10, which lies in the same plane 105 as the first-named ring, and to which the brush material is fastened by means of staples 9, each of which passes around a certain small bunch of bristles, and fastens the same together and tightly against the ring 110

2. In this type of brush the ring 1 serves the same purpose as in the previously described forms, while the ring 2 serves as a means for retaining the bristle fastening means, namely, the staples 9 adjacent to the loops in the bristles, and prevents these staples from working radially outward. At the same time this single ring 2 serves to maintain the bristles in the same plane in 10 the same manner as do the double outer rings shown in the other figures.

It is understood, of course, that these brush sections, such as I have described, are intended to be assembled and used on a suitable mandrel, and may be used either singly or in conjunction with a number of similar sections, and, of course, the presence of such a mandrel within the hollow center of the section also serves to prevent any of the bristles from working inward away from the inner rings 1.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. A rotary brush section comprising a base ring, brush material looped upon said ring, two other rings of larger diameter than

and concentric with said base ring and contacting with said material on the respective sides thereof radially beyond and wholly clear of said base ring, and means passing through said material at spaced intervals and locking said last-named rings together, whereby the loops of material are tied together and secured in place on said base ring.

2. A rotary brush section comprising a circular wire base, brush material looped upon said base, two other circular wires of larger diameter than and concentric with said base wire and contacting with said material on the respective sides thereof radially beyond and wholly clear of said base wire, and staples passing through said material at spaced intervals and locking said last-named wires together, whereby the loops of material are tied together and secured in place on said base ring.

3. A rotary brush section comprising a plurality of base rings lying side by side, brush material looped upon each of said rings, other rings of larger diameter contacting with said material on the respective sides thereof radially beyond and wholly clear of said base rings, and means connecting said last-named rings, whereby the loops of material are tied together and secured in place on said base rings.

Signed by me, this 20th day of June, 1918. 65
CLINTON E. FROST.
